DESIGN FOR A DRESS ENSEMBLE

Marie Mascitelli, New York, N. Y.

Application March 21, 1938, Serial No. 75,987

Term of patent 3½ years

To all whom it may concern:

Be it known that I, Marie Mascitelli, a citizen of the United States of America, residing in New York city, in the Borough of Manhattan, county and State of New York, have invented a new, original, and ornamental Design for a Dress Ensemble, of which the following is a specification, reference being had to the accompanying drawing, forming part thereof, wherein,

The characteristic feature of my design resides in the combination on the ensemble disclosed, of the lattice work embroidered jacket, dress bow and shoulder straps, as shown.

I claim:

The ornamental design for a dress ensemble, substantially as shown and described.

MARIE MASCITELLI.
